UPHOLSTERED SEAT

Karl Wilfert, Stuttgart-Degerloch, Germany, assignor to Daimler-Benz Aktiengesellschaft, Stuttgart-Untertürkheim, Germany

Application May 21, 1952, Serial No. 289,041

Claims priority, application Germany May 22, 1951

1 Claim. (Cl. 155—180)

My invention relates to an upholstered seat and, more particularly, to the attachment of the cover thereof to its supporting frame. More especially, my invention relates to upholstered seats or couches for automobiles.

It is the primary object of my invention to provide improved means for the releasable attachment of the cover of an upholstered seat to the supporting frame thereof which are inexpensive, simple to manufacture and reliable in operation.

It is a more specific object of my invention to provide means for releasably attaching the cover of an automobile seat to its sheet metal supporting frame in a manner which lends itself readily to manufacture by modern production methods.

Prior to the present invention it was a widely adopted practice to attach the lower margin of the cover of an upholstered seat to the metal supporting frame by inserting wooden bars or cords made of paper strip in sheet metal channel members forming part of the supporting frame and to nail the cover thereon. In another mode of attachment the margin of the pliable cover was reinforced by a pliable inserted cord, wire or cable and by contraction thereof shortening the length of such inserted member, was drawn under tension into outwardly opening channel members of the sheet metal frame being drawn thereinto in a direction transverse to the direction of the compression of the springs of the seat.

The attachment by nails, however, is cumbersome, time consuming and does not readily permit of a subsequent detachment of the cover. While the attachment by a contracted cord or the like offers the advantage of easy detachment of the cover for repair or cleaning, experience has shown that a cover so attached is liable to come off accidentally, particularly where the cover consists of leather or a plastic having a limited pliability thereby resisting the contraction by the cord into the channel member.

It is the object of the present invention to avoid the disadvantages of the prior attaching means and to afford a seat in which the edge of the cover is reliably attached to the supporting frame of the seat so that it will not come off accidentally but may be readily taken off, if the cover is to be repaired or cleaned or to be exchanged.

Further objects of the invention will appear from the detailed description of a preferred embodiment thereof by reference to the drawings; but it is to be understood that such detailed description serves the purpose of illustration rather than that of limitation of the invention. In the drawing:

Fig. 1 is a perspective representation of the seat of a motor vehicle viewed obliquely from the front, the cover sheet being shown partly removed to render the novel attaching means visible.

Fig. 2 is a vertical transverse section through the seat shown in Fig. 1, such section being substantially on line 2—2 of Fig. 1.

Broadly speaking, the upholstered seat shown in Fig. 1 comprises a base, a resilient pad carried thereby and a

2

cover of pliable material such as cloth or a plastic covering the resilient pad and extending downwardly towards the base being releasably attached thereto by the means to be described hereinafter.

5 In the present embodiment the base 4 consists of sheet metal having a bottom plate 3 and an upturned outer rim 7, the marginal portion 8 of said rim being bent outwardly and downwardly so as to constitute an inverted U-shaped channel member 9 which, as shown in Fig. 1, 10 extends on all sides around the base 4 to constitute a continuous side wall thereof. A plurality of helical springs 5 are placed on the bottom plate 3 and suitably attached thereto by suitable means such as clips 6 spot-welded to plate 3. The cover consisting of cloth, leather 15 or a plastic comprises a top portion 11 covering a resilient pad (not shown) placed on the springs and side portions 10 extending downwardly in the vicinity of base 4. A strip 13 of a comparatively stiff material such as cardboard or a plastic is fixed to the lower margin of the side 20 portions 10 of the cover so as to reinforce such margin. The width of the strip 13 is a multiple of its thickness so that the strip will readily conform to the circumferential profile of the supporting frame 4 when bent transversely but will effectively resist to any bending couple acting 25 within its plane. In the embodiment shown, the marginal zone of the side portion 10 of the cover is once wrapped around the strip 13 and fixed thereto by an adhesive. As shown in Figs. 1 and 2, the strip 13 is slipped into the U-shaped channel bar 9 and is held in a substantially vertical position therein by the tension of the springs 5 tautening the side portions 10 of the cover.

In attaching the cover to the seat the operator proceeds as follows: First the cover is so placed upon the cushioned pad carried by the springs 5 that the side 30 portions 10 are suspended in the manner indicated in Fig. 2 at 10', the springs 5 being relaxed and extended and the lower rim 12 of the cover reinforced by strip 13 assuming the initial position shown at 12' by dotted lines. Thereupon the operator applies a super-normal load to the seat 35 compressing all of the helical springs 5 until rim 12 reinforced by the strip 13 will have been lowered to the position shown at 12''. Thereupon the operator turns the strip inside up through 180° until its lower edge 12'' will arrive in front of the mouth of the channel bar 9. Then the seat will be relieved from the load permitting the springs 5 to raise the pad and its cover causing the upturned strip 13 to enter the inverted channel member 9 until it arrives in the position indicated in Fig. 2 in full lines. In this position the side portions 10 of the cover 40 are kept taut by the springs 5 and will maintain the strip 13 in the position shown in which it frictionally engages the walls of the channel 9.

Under a normal load imposed on the seat, the side portion 10 of the cover will not be lowered to an extent sufficient to permit the strip 13 to slip out of the channel 45 9 either under the effect of its weight or under the effect of the stiffness of the cover. Should it be desired, however, to take off the cover 10, 11 in order to repair, clean or exchange the same, one needs only to subject the seat to a load higher than normal so as to compress the springs 5 all at once to an extent exceeding the distance of the upper edge of strip 12 from the lower edge of the flange 8 of the channel member. Thereupon the strip 13 50 may be easily pulled downwardly out of the channel member 9 and the cover may then be taken off the seat.

In practical use of the seat it happens sometimes that a powerful local load is imposed on the seat, for instance by someone kneeling or stepping on the seat. Such load, however, will not result in an accidental detachment of the cover because the strip 13 is held within the channel 55 member 9 by the effect of those springs 5 as are positioned at the points not affected by the local load which springs 60 70

will keep parts of the side cover portions 10 taut. A local dislocation of the strip 13 from the channel member 9, however, is practically impossible because of the stiffness of the strip resisting a bending of the strip within its plane and because of the tight seat of the strip 13 in the channel member preventing a twisting of the strip 13.

From the foregoing description it will appear that the frame of the seat preferably constructed as a stamped sheet metal member is provided on its outside with a downwardly opening U-shaped channel member and that the margin of the cover side portions are reinforced by a wide strip of stiff but flexible material such strip being upturned inwardly through 180° and slipped upwardly into the inverted channel member being kept therein by the spring force exerted by the cushion springs. The strip may consist of metal, wood, cardboard, plastic or any other suitable material. It may be attached to the margin of the cover by an adhesive or by sewing or by any other suitable means. The marginal portion of the cover sheet may be wrapped around the strip once or several times.

Viewed under a broader aspect, my invention is applicable wherever a cover sheet is to be attached to a sheet metal supporting frame, for instance to the back of upholstered seats or to the arm rests thereof.

The pad beneath the cover may be firmly united therewith or may be formed by the helical springs themselves provided that a great number of small springs is provided.

Having now described my invention with reference to a preferred embodiment thereof, I wish it to be clearly understood that the same is in no way restricted to the details of such embodiment, but is capable of numerous modifications within the scope of the appended claim.

What I claim is:

In an upholstered seat, the cover of which may be readily installed and removed, the combination comprising a sheet metal base provided with an upwardly extending rim along the entire periphery thereof, said upwardly extending rim being bent back upon itself outwardly to provide a substantially inverted U-shaped channel between said upwardly extending rim and the bent back portion thereof, said U-shaped channel lying on the side of said upwardly extending rim opposite said base, a pad, spring means extending upwardly from said base for supporting said pad, a cover of pliable material extending downwardly on all sides of said base, a strip of stiff material affixed to the lower end of the downwardly extending portions of said cover for insertion into said U-shaped channel from below, said springs, said pad and said cover being so dimensioned as to normally exert tension on said cover, said strip being thereby progressively moved into a more secured position within said inverted U-shaped channel, and said strip being of greater dimension than the bent back portion forming the outer leg of said U-shaped channel so as to prevent contact between the lower edge thereof and said cover.
